UNITED STATES PATENT OFFICE.

MICHAEL KANIUK, OF BOYERTOWN, PENNSYLVANIA.

DESIGN FOR A DISH OR VESSEL COVER.

Application filed May 15, 1922. Serial No. 2,264. Term of patent 7 years.

To all whom it may concern:

Be it known that I, MICHAEL KANIUK, a citizen of Ukraina, residing at Boyertown, in the county of Berks and State of Pennsylvania, have invented a new, original, and ornamental Design for a Dish or Vessel Cover, of which the following is a specification, reference being had to the accompanying drawing, forming a part thereof.

I claim:

The ornamental design for a dish or vessel cover, as shown.

MICHAEL KANIUK.
